UNITED STATES PATENT OFFICE.

RICHARD WILLINSON BATEMAN AND LOFTUS HANSON BATEMAN, OF HALIFAX, ENGLAND.

DRIVING MECHANISM FOR PLANING OR LIKE MACHINES.

SPECIFICATION forming part of Letters Patent No. 767,789, dated August 16, 1904.

Application filed January 29, 1904. Serial No. 191,205. (No model.)

To all whom it may concern:

Be it known that we, RICHARD WILLINSON BATEMAN and LOFTUS HANSON BATEMAN, residing at Hanover street, Halifax, in the county 5 of York, England, have invented certain new and useful Improvements in the Driving Mechanism of Planing or Like Machines; and we do hereby declare the following to be a full, clear, and exact description of the invention, such as 10 will enable others skilled in the art to which it appertains to make and use the same.

This invention relates to improvements in the method of and means employed for driving planing, shaping, slotting, and other like 15 machines where it is necessary to quickly reverse the direction of motion of the table or of the ram.

The object of the invention is to facilitate the reversing of the machine by providing 20 means for stopping the machine when running in one direction and also instantly restarting the machine at full speed in the reverse direction and removing to a great extent undue strain and shock on the driving-belts and reducing to a minimum the power 25 required to stop the movement of the table or ram in one direction, and to restart it in the reverse direction by utilizing the power or stored-up energy generated in an extremely- 30 heavy wheel or pulley continuously revolving in one direction.

The invention consists of the use, in combination with the ordinary driving-pulley, of a heavy wheel or loose pulley, the momentum 35 of which is imparted to the driving-wheel by a wide driving-strap or by the driving-strap and frictional face-contact between such pulleys at the moment of reversal in the ordinary manner, so that the momentum of the heavy 40 wheel is utilized both for stopping and restarting.

Referring to the drawings which form part 45 of this specification, Figure 1 is a side elevation of the improved driving mechanism. Fig. 2 is a section through the driving-pulley and through the heavy loose pulley or fly-wheel. Fig. 3 is a plan view of the improved driving mechanism, showing the slide-cover broken away. Fig. 4 is an enlarged section

showing the clutch mechanism for forcing the 50 heavy loose pulley or fly-wheel against the driving-pulley. Fig. 5 is a section through line A B on Fig. 4. Fig. 6 is a section through line C D on Fig. 4.

According to this invention the planing- 55 machine is driven from the fixed pulley 1 on the driving-shaft 2, as ordinarily, and alongside of this and loose on the same shaft is the heavy loose pulley or fly-wheel 3. The latter is made broader than the driving-pulley for 60 the wide belt 4, which never entirely leaves the loose pulley 3. When the planer-table is being driven in one direction from one side of the machine, the belt on that side is over the fast or driving-pulley and also partly over 65 the loose pulley or fly-wheel 3, which consequently receives the same momentum as the driving-pulley 1 and is driven with it, the belt on the opposite side of the machine being entirely on the loose pulley or fly-wheel 70 3, and revolving in the opposite direction. When now the table is moved in the reverse direction, the belts on each side of the machine are moved over so that the belt which was formerly entirely on the loose pulley is now 75 transferred onto the driving-pulley. The momentum or energy stored in the loose pulley or fly-wheel 3 is imparted to the said driving-pulley at the very moment of reversing the movement of the table, the momentum of the 80 loose pulley 3 being then maintained by the wide belt 4, which, as aforesaid, never entirely leaves the loose pulley 3. By this means the great strain and shock put on the driving-belts every time the direction of movement of 85 the table is reversed is removed therefrom and is taken up by the momentum or energy stored up in the loose pulley or fly-wheel, and the table reverses instantly at its normal speed.

To increase the frictional contact between the heavy pulley 3 and the driving-pulley 1, the former has a concentric flange or rim 5 projecting therefrom and faced with felt or leather or other like material 6, and the above-mentioned rim engages with a similar rim or flange 7. The engaging surfaces of the above-mentioned flanges are cone-shaped in order to 90 95

obtain a better and more gradual application of the friction. The driving belt or strap 4 is transferred from the loose pulley 3 to the driving-pulley 1 by a mechanism which at the 5 same time that it moves the belt or strap 4 onto the driving-pulley 1 also tends to force the pulley 3 endwise on its shaft 2, so pressing the frictional surfaces of the wheels 1 and 3 together.

10 The above-mentioned mechanism consists of the ordinary strap-fork 8, fixed on the bar 9, supported by the standards 10. The bar 9 is connected by the swivel-joint 11 to the lever 12, free to rock on the pin or stud 13, supported in the frame 14. To the lower end of the stud 13 is fixed a short crank-arm 15, connected by the rod 16 and spring-escapement 17 to the crank-arm 18, fixed on the vertical shaft 19. The latter is supported at its upper end 15 in the bearing 20, and the lower end of such shaft (see Figs. 4 and 6) has a sector-pinion 21 supported in the foot-step 22 and engaging with the rack 23, formed on the sleeve of the coupling 24, to which is attached the two 25 semicircular plates 25, which engage with the annular ring 26 in the boss of the loose pulley or fly-wheel 3. The shaft 2 is preferably protected against wear by the bushes 27, which are fixed thereon, and the end thrust 30 against the driving-wheel 1 is taken up by the collar 28. (See Fig. 2.) The end thrust in the opposite direction is taken up by the antifriction-washers 29 and by the lock-nuts 30 on the end of the shaft 2.

35 The strap-fork mechanism is operated through the rod 31, (see Fig. 1,) which works in connection with the ordinary adjustable dogs for limiting the length of travel of the planer-table, the said rod being connected to the arm 32, carried on the bracket 33, and connected at its upper end by the link 34 to the slide 35, which is free to reciprocate in the slide-bed 36.

In the slide 35 is a cam-shaped slot 37 for 45 the bowl or runner 38, mounted on the lever 12, and as the slide is moved backward and forward through the above-mentioned connections the lever 12 is oscillated thereby and

the necessary movement is imparted to the strap-fork for transferring the belt from one 50 pulley to the other.

Having now described our invention, what we claim as new, and desire to secure by Letters Patent, is—

1. In driving mechanism, the combination, 55 with a driving-shaft, and a driving-pulley secured thereon and provided with a clutch member; of a heavy loose pulley also provided with a clutch member and journaled concentric with the said driving-pulley, a sleeve provided with a toothed rack and operatively connected with the said loose pulley, a rock-shaft provided with teeth which gear into the said rack, a lever secured on the said rock-shaft, a belt-shipper, a pivoted operating-lever connected to the belt- 60 shipper, and a connecting-rod between the two said levers, whereby the clutch members are placed in engagement when the belt is moved onto the driving-pulley. 65

2. In driving mechanism, the combination, 70 with a driving-shaft, and a driving-pulley secured thereon and provided with a clutch member; of a heavy loose pulley also provided with a clutch member and journaled concentric with the said driving-pulley, a sleeve provided with a toothed rack and operatively connected with the said loose pulley, a rock-shaft provided with teeth which gear into the said rack, a lever secured on the said rock-shaft, a belt-shipper, a pivoted operating-lever connected to the belt- 75 shipper and provided with a projection, a slide provided with an inclined slot engaging with the said projection, a guide for the said slide, means for sliding the said slide in its guide, and a connecting-rod between the two said levers, whereby the clutch members are placed in engagement when the belt is moved onto the 80 driving-pulley. 85

In testimony whereof we affix our signatures in presence of two witnesses.

RICHARD WILLINSON BATEMAN.
LOFTUS HANSON BATEMAN.
